UNITED STATES PATENT OFFICE.

JOHN A. WEBSTER, OF RUTHERFORD, NEW JERSEY, ASSIGNOR TO AUTOSALES GUM AND CHOCOLATE COMPANY, OF NEW YORK, N. Y., A CORPORATION OF NEW YORK.

COIN-OPERATED VENDING-MACHINE.

1,157,069.

Specification of Letters Patent.

Patented Oct. 19, 1915.

Application filed December 16, 1912. Serial No. 737,060.

To all whom it may concern:

Be it known that I, JOHN A. WEBSTER, of Rutherford, county of Bergen, and State of New Jersey, have invented certain new and useful Improvements in Coin-Operated Vending-Machines, of which the following is a specification.

My invention relates to coin-operated vending machines having a plurality of compartments, and has for its object the provision of a slot-closing device constructed to close the coin-slot when all of the compartments are empty.

In the drawings, Figure 1, is a front sectional elevation of a vending machine embodying my invention with a portion of the locking mechanism removed; the section being taken substantially on line 1—1 of Fig. 3. Fig. 2, is a detached view of the plate carrying the lid-locking levers. Fig. 3, is a vertical section of the machine on line 3—3 of Fig. 1. Fig. 4, is a section on line 4—4 of Fig. 3, showing the coin-entrance slot open for the passage of a coin. Fig. 5, is a similar view showing the slot closed against the introduction of a coin. Fig. 6, is a fragmentary detail view showing the cam surface in one of the locking plates for releasing the slot-closer; and Fig. 7, is a fragmentary detail view showing the slot-closer in operated position.

For the sake of illustration, I have shown my invention applied to a two-compartment machine like that shown in the Patterson Patent No. 840,513, January 8, 1907, or in my prior Patent No. 837,362, December 4, 1906.

In the accompanying drawings, 1 represents as a whole the casing formed with two compartments 2 and 3, provided with independent lids 4 and 5 for closing and sealing them. The lower portions of these compartments are provided with floors supported on projecting springs 6. The front wall 1^a of the casing has fixed thereto the reinforcing plate 1^b. The frame or plate 7 carried by the outer front wall or plate 7^a on the inner side thereof, is provided with a recess or cutaway portion having bottom edges 8 converging toward the coin slot 9. 10 are elongated grooves formed on the inside of the plate 7^a. At the lower end of each groove is a fixed lug 11 which extends inwardly from the inner face of the plate 7^a, as clearly shown in Figs. 4 and 5.

12 are slideable locking plates having a straight outer edge and an inner arcuate edge 13 terminating in a cam face 13^a; the lower edge 13^b of the plates being beveled to correspond with the lower edge 8 of the recess. These locking plates are provided with elongated slots 14 into which the lugs 11 project. In each of the slots 14 and groove 10 is a coiled spring 15, one end of which bears against the lug 11 while the other end bears against the upper end of the slot 14. The shoulder 16 on each locking plate is adapted to engage the shoulder 17 on the frame 7 to limit the upward movement of the locking plate. The extreme upper end of each locking plate is provided with a beveled cutaway portion 18, as best shown in Fig. 6. Into the recess of the frame 7 extends a pair of lugs 20 carried by the front wall 7^a. As seen from Figs. 4 and 5, each of these lugs has a straight edge which acts as a bearing for the locking plate 12, and a curved edge which forms a continuation of the arcuate edge 13 of the locking plate.

The inner face of the front plate 7^a is provided with a recess 21, at the coin-entrance slot 8^a formed in the frame 7. In the recess 21 is fitted a slot-closing plate 22, provided with a recess 22^a in which is secured a flat spring 23 by a rivet 23^a near the bottom thereof. The normal set of the spring 23 is such as to throw the plate 22 into closing position, as shown in Fig. 7, and thus close the slot 8^a against the passage of a coin and hold the coin in such position that it may readily be withdrawn. 80 The ends 22^a of the plate 22 in the embodiment shown extend beyond the lugs 20 into the path of the beveled portions 18 on locking plates 12. When one or both of the locking plates 12 are in upper or locking position, the beveled portions 18 hold the slot closer 22 in forward or inoperative position within the recess 21. However, when both plates are in lower or operated position, the slot closer is no longer held back, and the 90 spring 23 at once throws the same into the position shown in Fig. 7, to prevent the further deposition of a coin until the machine has again been replenished.

The plate 24 which covers the upper half 105 of the recess in frame 7 is provided with an elongated slot 25 near its bottom and with slots 26 and 27 at right angles to each other,

2
near its top edge. On the inner face of this cover plate 24 are forwardly extending lugs 29 which, when the plate is in position, bear against the lower portion of the closure plate 22, to retain the same within the recess 21, 5 the bevel on the lugs permitting the plate 22 to be projected into the coin slot 8^a, and limiting the movement thereof.

On the cover plate 24 are pivoted levers 30 10 by means of studs 30^a. The upper end of each lever is provided with lugs 31 and 32 adapted to project through the slots 26 and 27, and also with a rearwardly extending tongue 33 constructed to engage the covers 15 or lids of the compartments and lock them in closed position. When the plates 12 and levers 30 are in normal position, the lugs 31 enter the beveled recesses 18 to lock the levers 30 against unauthorized movement. 20 The lug 32 of each lever 30 projects into a slot 34 and is adapted to be engaged by a special key inserted in said slot for the purpose of restoring the lever to locking position.

35 is a transversely movable plate operating in the slot 35^a provided in the front wall 1^a of the casing. The levers 30 are accommodated in vertical slots 35^b extending from the slot 35^a. At its ends the plate 35 has lugs 36 constructed to engage the lower ends 30 of the levers 30 to move them to unlocking position when the plate 35 is moved to the extreme limit of its movement in one direction or the other. The plate 35 is held to 35 the cover plate 24 by means of the pins 36^a passing through the elongated slots 37. A projection 38 extends forwardly from the plate 35 through the slot 25 into the recess 40 of the frame 7. The plates 7^a, 7 and 24 are secured together and attached as one member to the front wall 1^a of the casing. The coin-retaining mechanism R (described in detail in the prior patents referred to) carried by the plate 7 is covered by the plate 40 24^a. A rotating coin disk 39 is pivotally mounted in the recess of the frame 7 and is provided with coin-receiving notches 40. This disk is operated by means of the knob 41 upon the outside of the case.

50 The operation of the machine, in view of the disclosure in the patents above referred to, need not specifically be described.

With the parts in the position shown in Fig. 2, the coin disk is revolved to the right 55 carrying the coin in the coin notch and impinging it against the cam face 13^a of the locking plate 12, on the right hand side, thus forcing the plate down until its upper end is below the lug 31 on the corresponding 60 locking lever 30. A continued movement of the disk impinges the coin against the projection 38 on the plate 35, and thereby moves the plate transversely, which, by means of the lug 36, swings the lever 30 on its pivot 65 until the tongue 33 registers with the notch

n in the cover of the right hand compartment, whereupon the spring 6 projects the package above the edge of the compartment for removal by the purchaser. On the introduction of another coin the coin disk is 70 revolved to the left and the operation above described is repeated.

After both locking plates are depressed into unlocking position, the slot-closure plate 22 is no longer under the influence of said 75 plates and is free to be projected into the coin slot by means of its spring 23 to close the slot against the introduction of further coins, until the parts are reset by the introduction of a special key in slot 34 for engaging the lug 32. In the resetting operation, the lever 30 is pushed into locking position, whereupon the corresponding locking plate 12 is free to be elevated by its 80 spring 15.

85 It may be found desirable to provide a separate coin slot for each compartment in which event the plate 22 will be divided into two parts, each part being acted upon independently to close its respective slot after the opening of each independent lid.

90 While I have herein shown and described my improved slot-closing device in connection with a specific form of coin-controlled locking mechanism, it will be understood 95 that in the broad aspect of my invention any form of coin-controlled locking mechanism may be used to properly co-operate with the slot-closing device.

Having thus described my invention, what 100 I claim as new and desire to secure by Letters Patent of the United States is:

1. In a coin-operated vending machine having a plurality of compartments and a common coin-slot therefor, coin-operated 105 mechanism associated with each compartment for controlling the same, means for closing said slot, and means whereby said mechanisms are adapted to normally hold said slot-closing means out of operative position and to release the same into closing position only when all of said mechanisms are in predetermined position.

2. In a coin-operated two-compartment vending machine having an independent lid for each compartment, a coin-slot common to both of said compartments, means for closing said slot, and coin-operated mechanism for controlling said lids and adapted to normally hold said slot-closing means out 110 of operative position and to release the same into closing position only when both of said lids are open.

3. In a coin-operated two-compartment vending machine having an independent lid for each compartment, a coin-slot common to both of said compartments, means normally tending to close said coin-slot, movable members for normally locking said lids and adapted when in normal position to hold 115

- said means in an inoperative position, and coin-controlled mechanism to move said locking members for releasing said slot-closing means.
- 5 4. In a coin-operated vending machine, the combination of a casing having two compartments, an independent lid for each compartment, a coin-slot common to both of said compartments, locking means for 10 each of said lids, a hand-operated coin-controlling device adapted to move said locking means into releasing position so as to unlock the lids, and means for automatically closing said coin-slot when the lids of both 15 compartments are unlocked, said slot-closing means being held in retracted or inoperative position by said locking means when one or both of said lids are locked.
5. In a coin-operated vending machine 20 having two compartments and a coin-slot arranged midway between the same, means for closing said slot, and coin-controlled mechanism on each side of said coin-slot for controlling said compartments and normally holding said slot-closing means out of operative position, said mechanism being adapted to release said means into closing position only when both mechanisms are in predetermined position.
- 30 6. In a coin-operated vending machine having two compartments and a coin-slot arranged midway between the same, a pivoted member for closing said slot, and coin-operated mechanism for controlling said 35 compartments and adapted to normally hold said member out of operative position and to release the same into closing position only when said mechanism is in predetermined position.
7. In a coin-operated vending machine 40 having two compartments and a coin-slot, a spring-pressed pivoted plate for closing said slot, and coin-operated mechanism for controlling said compartments and adapted to normally hold said plate out of operative 45 position and to release the same into closing position only when said mechanism is in predetermined position.
8. In a coin-operated vending machine 50 having two compartments with an independent lid for each compartment, separate means for locking each lid, a coin-slot common to both compartments, means for closing said slot, and coin-controlled mechanism adapted to normally hold said slot-closing means out of operative position and to release the same into closing position only 55 when both of said locking means are in unlocking position.
9. In a coin-operated vending machine 60 having two compartments with an independent lid for each compartment, separate means for locking each lid, a coin-slot common to both compartments, a spring-pressed pivoted plate for closing said slot, and coin-controlled mechanism adapted to normally hold said pivoted plate out of operative position and to release the same into closing position only when both of said locking means are in unlocking position. 70

In witness whereof, I hereunto subscribe my name this 9th day of December, 1912.

JOHN A. WEBSTER.
